CLAIM

The ornamental design for a wireless earphone, as shown and described.

DESCRIPTION

2.-3. Wireless earphone

2.1 is a front view of a left wireless earphone, showing the first embodiment of the new design;
2.2 is a back view of the left wireless earphone;
2.3 is a left view of the left wireless earphone;
2.4 is a right view of the left wireless earphone;
2.5 is a top view of the left wireless earphone;
2.6 is a bottom view of the left wireless earphone;
2.7 is a perspective view of the left wireless earphone;
3.1 is a front view of a right wireless earphone, showing the second embodiment of the new design;
3.2 is a back view of the right wireless earphone;
3.3 is a left view of the right wireless earphone;
3.4 is a right view of the right wireless earphone;
3.5 is a top view of the right wireless earphone;
3.6 is a bottom view of the right wireless earphone; and
3.7 is a perspective view of the right wireless earphone.
